UNITED STATES PATENT OFFICE.

WILLIAM S. PITCAIRN, OF EAST ORANGE, NEW JERSEY, ASSIGNOR TO WILLIAM S. PITCAIRN CORPORATION, OF NEW YORK, N. Y., A CORPORATION OF NEW YORK.

DESIGN FOR A PLATE OR SIMILAR ARTICLE.

Application filed March 1, 1923. Serial No. 5,335. Term of patent 7 years.

To all whom it may concern:

Be it known that I, WILLIAM S. PITCAIRN, a citizen of the United States, residing at East Orange, county of Essex, and State of New Jersey, have invented a new and original Design for a Plate or Similar Article, of which the following is a specification, reference being had to the accompanying drawing, forming part thereof.

Figure 1 is a plan view of a plate, showing my new design. Figure 2 is a cross section of the same on the line 2—2 of Fig. 1.

I claim:

The design for a plate or similar article as shown.

WILLIAM S. PITCAIRN.
